DESIGN FOR A COMBINED CHRISTMAS STOCKING AND GREETING CARD

Justin I. Kingson, Mount Vernon, N. Y.

Application August 22, 1940, Serial No. 94,557

Term of patent 7 years

To all whom it may concern:

Be it known that Justin I. Kingson, a citizen of United States and resident of Mount Vernon, in the county of Westchester, State of New York, has invented a new, original and ornamental Design for a Combined Christmas Stocking and Greeting Card, of which the following is a specification, reference being had to the accompanying drawing, forming part thereof, and in which,

Fig. 1 is a plan view of a combined Christmas stocking and greeting card, embodying my new design; and

Fig. 2 is an edge view thereof on a somewhat reduced scale.

I claim:

The ornamental design for a combined Christmas stocking and greeting card, substantially as shown.

JUSTIN I. KINGSON.
